J. B. HADAWAY

MANUFACTURE OF SHOES

Filed March 22, 1924

INVENTOR
John B. Hadaway.

UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MANUFACTURE OF SHOES.

Application filed March 22, 1924. Serial No. 701,221.

This invention relates to improvements in shoes and parts thereof.

In the manufacture of welt shoes an inner-sole provided with a sewing lip or rib about 5 its forepart and shank is secured to a last upon which the upper is assembled and over which it is lasted. The upper and a welt are then sewed to the rib or lip of the innersole by an inseaming operation. The inseam ex- 10 tends at each side of the shoe a short distance beyond the breast line, that is, the line where the plane of the breast of a heel, subsequently attached, will, if extended, intersect the plane of the shoe bottom. These end por- 15 tions of the inseam, even after the inseam trimming operation has been performed, project above the plane of the bottom of the innersole. A shank piece, such as a metal stiffener, is placed between the end portions 20 of the inseam with its rear ends in proximity to the breast line. The forepart and shank of the shoe are then filled. This filling, how- 25 ever, should not extend beyond the breast line because the heel-seat portion of the shoe bot- 30 tom upon which the rear end of the outsole rests requires no filling, and the presence of filling at the front part of the heel-seat, where the ends of the inseam and shank piece are located, would bring the front portion of the 35 heel-seat portion of the outsole, when laid over it, above the plane of the rest of the heel-seat and cause the front end of the heel, when attached, to be raised out of its normal po- 40 sition. In fact, the end portions of the in- 45 seam and the rear end of the shank stiffener, even in the absence of filling material, bear on localized areas of the outsole when it is ap- 50 plied and prevent the breast end of the heel-seat portion of the outsole from being brought into proper contact with the surface of the innersole, with the result that when the out- 55 sole is forced down upon the ends of the inseam and the unfilled space between them it is bent into an irregular curve transversely of 60 the shoe along the breast line, so that when the heel is attached and breasted the breasting knife does not have an evenly transversely curved surface to which to cut, with the result 65 that the breasting is difficult and the appear- 70 ance of the shoe is liable to be adversely af- 75 fected by reason of the uneven contour of the sole near the breast line.

In view of these conditions, an object of

this invention is to provide a shoe which will not only have the breast portion of its heel-seat in the same plane as the remainder of the heel-seat, but will also have an evenly transversely curved portion adjacent to the breast line to facilitate the breasting operation and enhance the appearance of the portion of the shoe adjacent to the heel-seat.

A feature of the invention consists in a shoe construction by which localized pressure between the outsole and projecting portions of the shoe bottom adjacent to the breast line is relieved. As shown, the outsole is thinned or recessed adjacent to the breast line of the heel, the thinning or recessing being laterally spaced to correspond to the distance between the ends of the inseam of the shoe to 70 which it is to be applied, so that when the sole is laid upon the shoe the localized pressure of the ends of the inseam will be relieved and the heel-seat portion of the outsole may be even- 75 ly laid upon the shoe bottom and given a uni- 80 form transverse curvature for the reception of the front portion of the heel.

Another feature of the invention consists in a shoe construction by which the pressure be- 85 tween the outsole and the rear end of the shank piece is relieved. As shown, the sole is thinned at the portion which covers the rear end of the heel stiffener, preferably by mak- 90 ing a recess in its inner face, this recess being somewhat wider and shallower than the re- cesses which accommodate the ends of the inseam. The requisite thinning may be pro- 95 vided by a plurality of recesses or, as also illustrated herein, there may be a single recess in the outsole of proper depth, size and shape to receive both the ends of the inseam and the rear end of the shank piece. In this form the outsole is particularly adapted for use in shoes having narrow shanks where the spaces between the shank piece and the inseam are narrow.

These and other features of the invention will be readily understood from the following description when read in connection with the accompanying drawing and will be 100 pointed out in the appended claims.

In the drawing,

Fig. 1 is a perspective view showing the inner face of an outsole made in accordance with the present invention;

Fig. 2 is a similar view of an outsole em-

bodying the invention in a different form; and

Fig. 3 is a perspective view, partly in section, of the heel end of a shoe with an outsole embodying the invention applied thereto.

In Fig. 1 a block sole A is represented as having its shank portion reduced at B, B, the reductions extending on the inner or flesh side of the sole along the margins of the shank 10 from the ball line to the breast line D—D. A machine for reducing shanks in this manner is disclosed in United States Letters Patent No. 1,382,689, granted June 28, 1921, on application of W. C. Stewart. Although the shank 15 reductions form no part of the present invention, they have been shown and the machine for producing them referred to for a reason which will later appear.

In accordance with the present invention, 20 thinned areas or recesses 2, 2 are formed on the inner face of the outsole to receive the ends of the inseam when the sole is applied to the shoe. These recesses therefore are located with their centers approximately at the breast 25 line represented by the line D—D in Fig. 1 and separated a distance equal to the distance between the ends of the inseam of the shoe for which the sole is intended. The depth of the recesses will preferably approximate the elevation of the inseam above the plane of the heel-seat.

Located centrally of the sole, with its greater portion forward of the breast line, is a larger and preferably shallower recess 4 to receive the rear end 6 of the shank piece.

In Fig. 2 is shown a sole in which the recesses 2 and 4 of Fig. 1 are combined or coalesced into a single recess 8, the side portions of which accommodate the ends of the inseam 40 and the central and forward portion of which receives the end of the shank piece.

Fig. 3 illustrates the outsole A applied to a shoe with the ends 10, 10 of the inseam lying in the recesses 2, 2 and the end 6 of the shank 45 piece in the recess 4. The outsole is thus permitted to seat firmly against the heel-seat portion of the innersole along the breast line without receiving localized support from the projecting portions of the shoe bottom such as 50 the ends of the inseam 10, 10 and the end 6 of the shank piece which would, in the absence of the recesses, cause the outer surface of the outsole transversely thereof along the breast line to assume other than its regular normal 55 curvature.

The recesses or thinned areas of the outsole may be produced in any convenient manner. In practice, however, it has been found advantageous to employ the machine of the Stewart 60 patent above referred to, which, by suitable modification of the matrix sleeves of the die roll, is adapted for the manufacture of this sole. As modified, the matrix sleeves of the machine are provided with suitable projec-

tions which cause the portions of the sole 65 where the recesses are desired to be pushed beyond the normal plane of the sole so that the required amount of material will be removed by the skiving knife. In this machine the reductions B, B may be made at the same 70 time or the recesses may be made without reducing the shank, the desired results being obtained by suitable modification of the matrix sleeves.

Although, for the purpose of illustrating 75 the invention, specific forms of recesses have been described, it is to be understood that the invention is not limited thereby, the novelty residing in a shoe construction by which pressure between portions of the shoe bottom adjacent to the front portion of the heel-seat is relieved locally, so that the breast end of the heel-seat portion of the outsole will not be raised above the remainder of the heel-seat portion and the outsole will not be distorted 80 in the region of the breast line.

Having described my invention, what I claim as new and desire to secure by Letters Patent of the United States is:

1. A shoe construction comprising an innersole, an upper attached to the innersole, and an outsole, the outsole being recessed locally adjacent to the breast line to relieve pressure between the outsole and parts of the innersole and upper and to prevent distortion 95 of the outsole at the forward portion of the heel seat.

2. A welt shoe construction, comprising a ribbed innersole, an upper and a welt secured to the rib by an inseam, said inseam 100 extending rearwardly of the breast line of the heel, and an outsole, said outsole being recessed locally to accommodate the ends of the inseam and having an undistorted heel-seat portion.

3. A welt shoe construction, comprising a ribbed innersole, an upper and a welt secured to the rib by an inseam, said inseam extending rearwardly of the breast line of the heel, a shank stiffener having its rear end 110 located adjacent to the breast line, and an outsole, said outsole having its thickness reduced adjacent to the end of the inseam and to the rear end of the stiffener to relieve pressure of these parts upon the sole, the breast 115 portion of the heel-seat of the sole being consequently undistorted with respect to the remainder of the heel-seat portion of the sole.

4. An outsole for shoes having its thickness centrally reduced locally at and adjacent to the breast line only to relieve pressure thereon of projecting portions of the shoe bottom.

5. An outsole for shoes having thinned areas adjacent to the ends of the inseam to 125 relieve pressure of the inseam upon the sole.

6. An outsole for shoes having recesses in its inner face located adjacent to the breast

line and spaced laterally of the sole to receive the ends of the inseam.

7. An outsole for shoes having a shallow recess in its inner face to receive and support the rear end only of a shank piece.

8. An outsole for welt shoes recessed in its inner face to relieve pressure on the in-

seam and the rear end of the shank piece to prevent distortion of the outsole in the region of the breast line.

10

In testimony whereof I have signed my name to this specification.

JOHN B. HADAWAY.
